UNITED STATES PATENT OFFICE.

NIKOLA TRBOJEVICH, OF DETROIT, MICHIGAN.

METHOD OF GENERATING GEARS.

Application filed June 25, 1923. Serial No. 647,670.

The invention relates to a novel method of gear generating which is applicable to milling or grinding of spur gears having either straight or helical teeth. In particular, this method is a combination of the well known hobbing and the fly-tool methods, and unites the advantages of both methods to such an extent that it is capable of producing gears having accurate and smoothly finished tooth surfaces, in a continuous and rapid cutting operation.

The elements which make up this method are a novel hob or milling cutter, a novel grinding wheel a novel generating machine and a novel wheel truing device, all of which are also inventions of mine. However, this application deals with the method of generating only.

In the drawings:

Figures 1 to 10 and Figure 21 are diagrams explaining the mathematical principles involved;

Figure 11 is a side view of my improved hob;

Figure 12 shows the same hob in plan view;

Figure 13 is a fragmentary view of my improved hob of the "milled tooth" type.

Figure 14 is a meridian section of my improved helicoidal grinding wheel;

Figures 15 to 17 illustrate my novel method of wheel dressing;

Figure 18 is the front elevation of a typical generating machine adapted to grinding of spur gears according to my method;

Figure 19 is the side elevation of the machine;

Figure 20 is the plan view thereof;

Figure 22 illustrates a method for simultaneously generating the opposite sides of the gear teeth.

In order to understand this new process of gear cutting, it is necessary first briefly to refer to the mathematical principles upon which the process is founded. It is known that an involute gear is defined by the fact that it correctly meshes with a rack having equi-spaced teeth composed of plane segments only. It may be stated broadly that all involute surfaces may be generated by a rolling-off process, from a plane. Therefore, in all gear generating processes now used, the imaginary rack plane forms an indispensable factor, and the cutting tool, either by its particular form, or by its move-

ment, describes in some manner the imaginary rack plane from which the particular gear is developed. Thus, the generation of a gear may be theoretically divided into two steps: first, the reproduction of the rack plane by the cutting edges of the tool and second, the rolling off process or the developing of tooth surfaces from said plane or planes.

In Figures 1 and 1^a, the principle of the ordinary hobbing process is shown. The gear blank A meshes with a rotating worm B having a length greater than

$$W = \frac{D}{\tan \beta} \quad 70$$

where D is the depth of tooth and β is the angle of pressure. It will be seen that the ordinary hob is equivalent to a rack of an infinite length and an infinitesimal width. In order to generate a blank A having a width f it is necessary that the imaginary rack should have the width f , at least. For this reason the hob must be translated along the axis of the blank. It is interesting to note that if the hob were of an infinite diameter it would not be necessary to have a special longitudinal feed movement. In that case a gear blank might be correctly generated by the intermeshing action alone of the hob and the blank.

Figure 2 shows another principle of generating, which is different from hobbing. A conical fly tool F having a plane cutting face d is inclined with respect to the tangent plane of the blank to an angle β , and is translated tangentially as indicated by the arrow while the blank rotates in unison, that is, has a pitch line velocity equal to the velocity of translation of the cutter. The diameter of the cutter F is comparatively large with respect to the width of the blank f (Figure 3), so that it may finish the tooth surfaces b , b_1 , b_2 etc., one in each stroke (Figure 3). Evidently, so far as the generation of the gear A having the comparatively narrow width f is concerned, the tool F is equivalent to a rack of infinitesimal length, but of an infinite width. Thus, in this method, the longitudinal feed is not necessary. However, it is necessary to reciprocate the tool tangentially, and to index the blank between the strokes in order to expose the surfaces b , b_1 , b_2 etc. successively to the generating action of the tool. Fur-

thermore, in order to generate the opposite curves c , c_1 , c_2 , etc. the blank must be reversed on its arbor and the process repeated.

- The fly tool method as shown in Figures 6 2 and 3, is extensively used in gear grinding. Its advantages are that it finishes the whole face of the tooth in one cut, without the longitudinal feed, and therefore, produces a good finish. Also the cutting face 10 d being a plane, is comparatively easy to accurately reproduce in the grinder. There is, however, a drawback inherent to this method and that is the need of mechanical indexing between the strokes of the tool. 15 Not only that a portion of the cutting time is thus non-productively spent in indexing, but the intermittent indexing operation also inevitably leads to more or less irregular spacing of teeth, which latter is a serious defect in a gear.

In my new method, a cutting tool of a novel form is used. The cutting surface is a right helicoid e , limited by two parallel and co-axial cones (Figure 5). It is well 25 known from mathematics that the right helicoid is a mathematically unique surface, as it approaches its tangent plane the most intimately of all twisted surfaces. In the language of mathematics, the surface is the 30 only real minimal ruled surface, (Theorem of Catalan), and has the property that its generators (the radial lines and the helixes) first form an orthogonal system, and second, are the asymptotic lines of the surface. 35 Therefore, the tangent plane T at any point Q of the surface (Figure 6) which latter is defined by the particular helix $\rho = \text{const.}$ and the particular radial line $\phi = \text{const.}$ passing 40 through it, intersects and osculates the surface e along said two lines at right angles. It is easily proved that if a comparatively small segment having the length f and the radial width D is cut out from a right helicoid having a comparatively large radius R 45 and a small lead of thread L , Figure 4 said segment may be considered for all practical purposes as a plane parallelogram, as the distances Δz_1 and Δz_2 separating the surface from its tangent plane T are extremely 50 small. I have calculated that if a cutter of only 10 inches diameter is used to cut 10 diameter pitch gears having a pressure angle $\beta = 20$ degrees and a width of face 1 inch, the maximum Δz (in the four corners) is 55 less than 0.0001" while the same distance on the pitch line is less than 0.00001".

Thus, it is seen that my invention consists mainly in finding a new form of a hob having a tapering helix, and a right helicoidal cutting face, the radius of curvature of which face may be considered as infinite for all practical purposes. Such a hob acts, then, as a rack having doubly infinite dimensions, that is, it acts with a continuous 60 intermeshing action, the same as the com-

mon hob, and yet it finishes the full width of the gear face in one cut, the same as the aforementioned conical fly tool. I have calculated that if the same effect was to be obtained by the spur hob of the conventional design, as is obtainable by this novel hob of only 10 inches diameter 10 pitch, the diameter of such a hob would have to be over 80 feet.

The method of calculating the amount of discrepancy of the surface from its tangent plane (the rack plane) at any point is the following. The equation of the helicoid e (Figure 5) may be written down and also the equation of its tangent plane at any point Q (Figure 6 and Figure 10). A circular ring segment P_1, P_2, P_2', P_1' , having a width f (Figure 10) is cut out both from the helicoid e and its tangent plane T . The difference between the corresponding z coordinates of the two surfaces will be always equal to, or greater than the actual distance between said surfaces and is indicative of the error in tooth curves at that particular point.

The equation of the surface is

$$\begin{aligned} x &= \rho \cos \phi \\ y &= \rho \sin \phi \\ z &= \frac{l_0}{2\pi} \phi \end{aligned} \quad (1)$$

where ρ and ϕ are the parameters (see Figure 5) while l_0 is the lead of the helix measured along the Z axis.

The equation of the tangent plane is obtainable from (1) by forming first the partial derivatives of x , y , z , with respect to ρ and ϕ and by placing said values in the well known determinant $\Delta=0$. To simplify the calculation, we determine the tangent plane at the point Q (R, O, O). Denoting the current coordinates with ξ, η, ζ we have then as the equation of said tangent plane

$$\xi = \eta \frac{l_0}{2\pi R} \quad (2)$$

where R is the pitch radius of the helicoid.

To find the errors at the points P_2, P_2' , and P_1 (Figure 10) we successively substitute the values of η_2, η_0 , and η_1 in (2). Thus for P_2 we find

$$\xi_2 = (R + s) \sin \phi_0 \frac{l_0}{2\pi R} \quad (3)$$

while from (1)

$$z_2 = \frac{l_0}{2\pi} \phi_0 \quad (4)$$

Hence the error

$$\Delta z_2 = z_2 - \xi_2 \quad (5)$$

In order to obtain a formula which is sufficiently close and yet simple, I have developed the equation (5) into an infinite series, and after omitting the infinitesimals of

higher order, have found the following values:

Error on the pitch line:

$$5 \quad \Delta z_0 = \frac{f^3 \cos \beta}{96 P R^3} \quad (6)$$

Error on the outer corner:

$$10 \quad \Delta z_2 = \frac{f \cos \beta}{4 P^2 R^2} + \Delta z_0 \quad (7)$$

where f is the width of face of the gear, R the pitch radius of the cutter in inches, β the cone angle or the angle of pressure, P the diametral pitch. It is also assumed that 15 the gear tooth has a standard addendum and dedendum

$$s = \frac{1}{P}.$$

20 Figures 7-9 show the relative positions of the helicoid with respect to the rack plane T on the pitch helix, on the root helix, and on the outside helix respectively, while from Figure 6, an idea may be had of the peculiar 25 osculating contact of the surface with said plane. In particular, the dotted line g shows the locus inside of which the error is everywhere less than a certain assumed Δz .

From the above explanation the principle 30 of operation will be understood. The conical hob G , Figure 4, acts in a double capacity, first as a spur hob B , Figure 1, and second as a conical fly-tool F , Figure 2. The hob G is rotated and tangentially translated as indicated by the arrows (Figure 4) while the blank A is also rotated to maintain the proper timed relation. In consequence, 35 all the curves b, b_1, b_2 etc. are simultaneously generated in a single passage of the tool, and furthermore, a blank having a considerable width of face f is fully generated over its entire face without the need of a longitudinal feed. The several advantages 40 of this method are obvious; first there are no longitudinal feed marks on the tooth surfaces such as are found in the ordinary hobbed gears; second there are no "flats" on the tooth curves on account of the tangential feed which makes the hob appear as if 45 it has an infinite number of gashes; third, the hob may be made quite narrow, and in my preferred construction it has always less than one full convolution of the helix compared with at least three full convolutions 50 necessary in the ordinary hob which has no tangential feed. When the process is used for grinding, the advantages become even more important, as this is to my knowledge 55 the first practicable process ever evolved for grinding gears in a continuous intermeshing generating operation. Owing to the fact that less than one full convolution of the helix is sufficient to properly generate the 60 tooth curves, the helicoidal face of the grinding wheel being readily accessible at every 65

point, may be accurately trimmed by means of a diamond without any great difficulty, as it will be presently shown.

The method of generation consists of the following steps: A tapered hob is first selected having a cone angle equal to the angle of pressure to be generated, and a diameter and pitch selected with reference to the gear to be generated. Said hob is placed in such a position relatively to the blank that its cutting face (the segment P_1, P_2, P_2', P_1' , Figure 10) coincides with the rack plane segment T from which the gear is developed. It will be understood that in this manner both straight and helical teeth may be generated as required. Third, the hob and the blank are rotated in a timed relation and a relative movement of translation is imparted to the hob in a direction perpendicular to the face of the blank. In such a manner the sides of teeth b, b_1, b_2 etc. (Figure 4) facing the generator g are fully generated. The opposite sides c, c_1, c_2 etc. may be generated either by employing another cutter inclined in the opposite direction or by reversing the blank on its arbor and repeating the process.

Figure 22 illustrates a method for simultaneously generating the contour of the gear teeth upon opposite sides thereof. The two cutters or grinders 73 and 74 are arranged 95 so that their respective cutting faces 75 and 76 coincide with opposite sides of the rack element T' , sufficient clearance between the cutters being provided by allowing one or more intervening rack tooth spaces. The 100 grinder 73 is provided with a right hand and the grinder 74 is provided with a left hand helix, one being rotated oppositely of the other as shown by the arrows. It will be apparent from the drawing that while 105 the grinder 73 is generating one side of the tooth 77, the other grinder is generating the opposite side of the tooth 78.

In grinding, the method is not complete without providing suitable means for intermittent dressing or truing up the cutting surface of the emery wheel. For cutting or grinding of helical teeth means must be provided for tilting or swiveling the cutter about an axis perpendicular to the common 110 tangent plane, in order to bring the cutting helicoid in complete tangency with respect to the imaginary rack plane T . Having thus described my method proper, I shall also 115 briefly describe its novel elements, namely, 120 the hob, the grinder, the generating machine and the wheel dressing device.

The hob.

Figure 11 and Figure 12 are two projections of my improved tapered hob of the "backed-off" type while Figure 13 shows a fragment of hob of the "milled tooth" type. The cutting helicoid e is first turned or milled in the truncated cone blank G , after 130

which a number of equi-spaced gashes or flutes *i* are milled across the helical thread, and the remaining teeth *j* are relieved by a movement of the relieving tooth perpendicular to the side of the cone. It will be seen that such a hob may be also ground after hardening all over, and in that manner a cutting tool of an utmost precision is obtained. It is also possible to repeatedly 13 sharpen the hob in the faces *i* without changing its correct tooth form.

The "milled tooth" type hob shown in Figure 13 is similar to the hob above mentioned in every respect, except that in the latter 15 case the teeth *j* are sharpened along the "lands" *k* and not in the gashes as is done in the preferred type.

The grinding wheel.

20 The grinding wheel is similar in every respect to the hob shown in Figures 11—12, except that it usually has a much larger diameter, is made of abrasive material and has no gashes or teeth as has the steel hob. A 25 grinder of this kind is first turned in a lathe to an approximate shape (see Figure 14) balanced both statically and dynamically, after which its cutting helicoidal face *e* is trued up by means of a trimmer diamond. 30 Figure 14 shows a suitable cross section that might be given to such a wheel in order that it may be repeatedly trimmed without losing its form. The successive trimmed surfaces are the helicoids *e*, *e*₁, *e*₂ etc. and the cones 35 *m*, *m*₁, *m*₂ etc.

The wheel dressing device.

To my knowledge I am the first to discover that it is possible to dress a grinding 40 wheel to a helicoidal or otherwise curved or irregular cutting contour by rotating the wheel only slowly, by mounting the trimming diamond eccentrically on a spindle running at a high rate of speed, and by giving the trimming spindle a movement of 45 translation relatively to the wheel and in a timed relation with respect to the rotation of said wheel. I consider this discovery as being of great practical importance as it 50 enables me to employ the hobbing principle for grinding of gears. It has been repeatedly suggested in the art prior to my invention, that gears should be ground on the hobbing principle, but no one has yet produced means for accurately and quickly 55 dressing the wheel to the required helicoidal shape. Now it is possible to accomplish that, and my tapered hob method is particularly suitable for that purpose because in that 60 method less than one full convolution of the helix is sufficient to properly generate the involute tooth curves.

Figures 15—17 show the new principle of 65 dressing abrasive helicoidal surfaces. The diamond 21 is mounted on a rotary spindle

22 and driven either by a pulley 23 or by a small electric motor (not shown). The movement of the grinder G₁ is entirely independent of the rotation of the trimmer 21 on its axis. Grinder G₁ is mounted on the 70 auxiliary spindle 24, one end of which is formed into an accurate master screw 25 engaging the fixed nut 26 and having the exact lead of helix as is desired in the grinder, while the other end of the spindle 75 24 is formed into a smooth journal 27 housed in the bearing 28 and longitudinally movable in the same. A large spur gear 29 is keyed to the spindle 24 and may be operated by means of the long pinion 30 and the 80 handwheel 31. It will be understood that when the handwheel 31 is rotated the grinder G₁ will describe a helical path, and its cutting surface *e* will be properly trimmed by the diamond 21 rotating in a stationary 85 plane. Figure 16 shows that when the trimmer 21 rotates about the axis 22 it describes cycloids *n*₁, *n*₂ etc. on the face of the grinder G, and it will be seen that if the diamond 90 rotates very rapidly with respect to the rotation of the grinder, the spacing of the cycloids *n*₁, *n*₂ etc. will be so close as to give to the grinder a smooth and true cutting face. Figure 17 shows a modification 95 of my wheel truing device. The diamond 21 first trues up the hard auxiliary grinder 32, while that wheel trims the softer main wheel G₁. The object of this arrangement is to shorten the time required for dressing 100 of the main wheel, and also to save the diamond from excessive wear.

The generating machine.

A machine embodying my invention and adapted to grinding of spur gears is shown 105 in three views in Figures 18—20. The general organization of such a machine is not broadly new, as there were in use prior to my invention hobbing machines operating 110 on the principle of tangential feed. Such hobbers were mainly used for hobbing of worm gears by means of a fly-tool or a tapered hob.

Referring now to Figure 18, the grinder G₁ is securely mounted on the end of the spindle 33 which is housed in suitable bearings 34 and 35 and is driven by means of the pulley 36. The mounting of the grinder head on the vertical column 37 is such that the wheel may be raised or lowered and also clamped in any intermediate position. The vertical adjustment is necessary in order to permit of using grinders of various diameters and also of grinding gears of different sizes. The axis of the cutter G₁ is inclined 120 with respect to the horizontal plane to an angle equal to the angle of pressure which it is desired to generate.

In order to transmit the timed rotation 130 from the cutter to the work, a mitre

is mounted upon the end of the spindle 33 furthest from the grinder. Said mitre meshes with the similar mitre 39 on the shaft 40, at the end of which shaft a universal joint 41 actuates the telescopic shaft 42, the second universal joint 43, the shaft 44, the mitres 45 and 46, the shaft 47, the change gears 48, 49, 50 and 51, the splined shaft 52, the main worm 53, the worm gear 54, the work spindle 55 and finally the gear to be ground 56. By suitably selecting the change gears 48 to 51 any number of teeth in the blank 56 may be ground.

The feed movement in this machine is entirely independent from the main timed rotation of the cutter and the blank, and may be operated either by hand or by power, without disturbing said timed relation. In order to accomplish this, a differential mechanism is employed, said mechanism consisting of two screws and two slides connected with change gearing.

The work spindle 55 is housed in the work head 57 which is a substantial casting and is slidably mounted on the top of the base 58. The handwheel 59 is mounted on the end of the feed screw 60 which is housed in the bracket 61 and engages the nut 62 in the work head 57.

The main drive worm 53 is made of a sufficient length and is housed in two bearings 63 and 64 integral with the differential slide 65. Said slide is mounted in the ways 66 of the base 58 and is actuated from the handwheel 59 through the differential change gears 67, 68, 69 and 70, the screw 71 and the nut 72. The arrangement is such that when the workhead 57 carrying the worm gear 54 moves in a certain direction, the differential slide 65 carrying the worm 53 moves in the opposite direction. In such a manner a proper increment of rotation may be imparted to the blank to compensate for the feed movement.

The action of said differential may better be understood from the Figure 21. In order to translate the gear blank 56 through a distance S_1 , both the blank and the worm gear 54 must receive the increment of rotation w_1 where $r_1 w_1 = S_1 = r_2 w_2$. It will be understood that for a feed of S_1 inches the worm 53 must be pulled back a distance equal to $S_2 - S_1$ where $S_2 = r_2 w_1$.

The wheel dressing device such as was shown in Figure 15 or Figure 17 is preferably mounted on the generating machine itself as a permanent fixture, although it might prove practicable to dress the grinding wheel in a separate machine. Said device has been omitted from the machine views Figure 18 to Figure 20, in order to make the drawings clearer.

What I claim as my invention is:—

1. A method for generating gears consisting in placing a right helicoidal tapering

cutter having a conical pitch surface and a conical helix forming in plane development an Archimedean spiral in relation to the work, such that the helicoid is tangent to the imaginary rack plane generator and in 70 rotating said cutter and work in timed relation.

2. A method of gear generating in which a right helicoidal tapered hob the helix of which forms in development an Archimedean spiral and the cone angle, diameter and pitch of which are selected with reference to the gear to be generated, is placed in a tangential relation with respect to the imaginary rack plane meshing with said gear at 80 about the middle of its face, in which the cutter and the blank are rotated in a timed relation and the cutter is given a relative movement of translation in a direction transverse to the axis of blank. 85

3. A method of gear cutting consisting in rotating the blank and a right helicoidal tapering cutter the generating helix of which forms in plane development an Archimedean spiral in a timed relation in such a manner 90 that the gear teeth and the helicoid while intermeshing are both tangent to a common rack plane, and in imparting a relative movement of translation to the cutter across the teeth of the blank. 95

4. A method of gear cutting consisting in rotating the blank and a right helicoidal tapering cutter having less than one full convolution of helix in a timed relation in such a manner that the gear teeth and the helicoid while intermeshing are always tangent to a common rack plane, and in imparting a relative movement of translation to the cutter in a direction perpendicular to the axis of the blank. 105

5. A method for grinding gears which consists in placing a grinder having a conical helicoidal abrasive surface the pitch helix of which forms in plane development an Archimedean spiral in such relation to the 110 gear to be ground that said surface is tangent to the imaginary rack plane generator and in rotating said gear and grinder in timed relation.

6. A method of gear grinding consisting 115 in rotating the blank and a conical helicoidal grinder the pitch helix of which forms in plane development an Archimedean spiral, in a timed relation in such a manner that the gear teeth and the helicoid while intermeshing are always tangent to a common rack plane, and in imparting a relative movement of translation to the grinder across the teeth of the blank. 120

7. A method of gear grinding consisting 125 in rotating the blank and a right helicoidal tapering grinder having less than one full convolution of helix in a timed relation in such a manner that the gear teeth and the helicoid while intermeshing are always tan- 130

gent to a common rack plane, and in imparting a relative movement of translation to the grinder in a direction perpendicular to the axis of the blank.

- 5 8. A method of gear grinding in which a right helicoidal tapered grinder having less than one full convolution of helix, and having the cone angle, the diameter and the pitch selected with reference to the gear to 10 be generated, is placed in a tangential relation with respect to the imaginary rack plane meshing with said gear at about the middle of its face, in which the grinder and the blank are rotated in a timed relation, in 15 which the grinder is given a relative movement of translation in a direction transverse to the axis of the blank, and in which the cutting helicoidal face of the grinder is periodically trimmed to a correct shape by 20 means of a rapidly rotating trimming element while the grinder simultaneously slowly rotates and axially translates in order to produce the required lead of helix.

9. A method of gear grinding consisting 25 in rotating the gear blank and a right helicoidal conical cutter of constant pitch and made of abrasive material, in a timed relation to produce the intermeshing action; in

feeding said cutter relatively across the face of the blank, and in periodically trimming the cutting helicoidal face of the grinder to a correct contour by means of a rapidly rotating trimming element while the cutter simultaneously slowly rotates and axially translates to produce the required lead of helix. 30

10. A method of hobbing spur gears and the like which consists in rotating two conical hobs of a constant conical pitch in a timed relation to a cylindrical gear blank, 40 and in arranging said hobs in such a manner that one side of the gear teeth is generated by one hob and the other side of said teeth is generated by the other hob during the same cutting operation. 45

11. A method of hobbing spur gears and the like which consists in selecting a pair of conical hobs having teeth with opposite sides of different radii of curvature, in rotating said hobs in timed relation to a gear blank, and in arranging the hobs in such relation to the gear blank that the hob teeth having greater radii of curvature generate the opposite sides of the gear teeth. 50

In testimony whereof I affix my signature.
NIKOLA TRBOJEVICH.
